his ATTORNEY.

UNITED STATES PATENT OFFICE.

FREDERICK W. POPE, OF ROXBURY, MASSACHUSETTS.

GAS RETARDING AND ADJUSTING DEVICE.

Application filed May 28, 1924. Serial No. 716,361.

To all whom it may concern:

Be it known that I, FREDERICK W. POPE, a citizen of the United States, residing at Roxbury, county of Suffolk, and State of Massachusetts, have invented certain new and useful Improvements in Gas Retarding and Adjusting Devices, of which the following is a specification.

This invention relates to a device for retarding and adjusting the flow of hot gases through boiler tubes. Heretofore in an endeavor to retard the flow of gases resort has been had to placing a spirally curved lath inside the tube which spiral extended the whole length of the tube, or else a bushing of some sort was inserted in the tube, but these devices collected soot and dirt and were difficult to insert and remove from the tube for the purpose of cleaning the tube. Furthermore, none of these devices could adjust the flow of gas in the tube. It is the primary object of the present invention to provide a device by means of which the flow of gas may be retarded and adjusted through a particular tube or through a particular nest of tubes in a boiler, making the circulation of gases uniform throughout the boiler. Another object of this invention is to provide a retarder that may be readily mounted in and removed from the tube without interfering with the adjacent retarder or tube. A further object is to provide a retarder and adjuster that permits the blowing or cleaning of the boiler tubes without its removal. A still further object is to provide a retarder and adjuster that is adapted to expand and contract. A further object is to provide a retarder and adjuster that is simple and economic to manufacture.

The invention will be more fully explained hereinafter with reference to the accompanying drawings in which it is illustrated and in which—

Figure 1 is a front view of the improved device shown in position, parts of the device in the lower tube being broken away in the interest of clearness.

Figure 2 is a cross section of Figure 1 taken on the plane indicated by the line 2—2 and looking in the direction of the arrows, the retarder in the lower tube being shown in elevation.

Figure 3 is a modification of the improved device.

Figure 4 is a cross section of Figure 3

taken on the plane indicated by the line 4—4 and looking in the direction of the arrows.

Figures 5 and 6 are detail views showing the choker plates with bores of different size.

Similar characters of reference designate corresponding parts throughout the various views.

As is well known the boiler plate *a* of the boiler is provided with a number of holes into each of which is fitted a tube *b* made of wrought iron, steel or any suitable material. The tube *b* is secured by means of the bead *c*. These tubes *b* serve to convey the flame, smoke and hot gases from the fire box to the smoke stack, and at the same time their sides provide ample heating surface to allow the heat contained in the products of combustion to escape into the water. In operating a boiler, it is desirable that the flow of gases be as uniform as possible throughout the tubes in the boiler. This is accomplished in the present invention by retarding and adjusting the flow of the gases through any particular tube or tubes by inserting the improved device in the desired tube or tubes. This retarding and adjusting device comprises a tubular portion *d* and a flanged or outboard portion *e* and may be made of any suitable material. The tubular portion *d* is slightly tapered as indicated at *f* so as to provide a snug fit within the tube *b*. A slot *g* extends the entire length of the tubular portion *d* through its upper section. This slot *g* permits the tubular portion *d* to expand and contract, and in addition affords a snug fit. The interior edge of the tubular portion *d* is beveled as indicated at *h*. The flanged or outboard portion *e* terminates at one end in a shoulder *j*. When the retarder is in position in the tube *b*, this shoulder *j* rests against the bead *c* of the tube and insures a tight joint at this point. The other end or face *k* of the flanged portion *e* is cut at a plane at an angle to the vertical; that is to say, it is beveled. The upper section of the flanged portion *e* has an annular slot *m* for one half its circumference. This slot *m* is cut at the same angle as the face *k*. The lower section of the flanged portion *e* has an annular groove *n* on its interior surface extending for one half of the circumference of the flanged portion *e* and in alignment with the slot *m* in the upper section of the

110

flanged portion *e*. The width of the slot *m* and the groove *n* is the same. Into the slot *m* is placed a choker plate *o*. This choker plate *o* comprises an enlarged portion *p*, a 5 smaller portion *q*, a bore *r* and shoulders *s*. Figures 5 and 6 show choker plates with bores of different diameters. When the choker plate is slid into the slot *m* the top of the plate is flush with the top of the 10 flanged portion *e* and the bottom or smaller portion *q* of the plate rests in the groove *n*. The shoulders *s* rest on the seats *t* provided by the slot *m* and in this way the plate is prevented from rocking or moving out of 15 place. By reason of the construction of the plate *o*, when it is in position in the flanged portion *e*, the bore *r* of the plate is eccentric to the bores or openings in the tubular portion *d* and the tube *b*. And by 20 reason of the beveled cut or slot *m*, when the choker plate *o* is removed from the flanged portion *e*, it is not lifted out of the flanged portion *e* in a vertical plane but in a plane at an angle to the vertical as will 25 be seen from Figure 2, thus avoiding contact with the adjacent tube about it.

In the modification shown in Figures 3 and 4, the annular groove in the lower section of the flanged portion *e* is missing and 30 the smaller portion of the choke plate *o* rests on the inner surface of the lower section of the flanged portion *e*.

In practice, the retarding and adjusting device is inserted in the smoke box end of 35 the tube *b*, the shoulder *j* resting against the bead *c* to insure a gas and water tight joint at this point. The tapered tubular portion *d* and the longitudinal slit *g* therein afford a snug fit and permit expansion 40 and contraction of the tubular portion *d*. The opening through the tubular portion *d* and the flanged portion *e* of the improved device is of a smaller sectional area than the sectional area of the boiler tube and 45 by reason of this construction the flow of gas through the boiler tube is retarded to a certain degree. To retard the flow still further and to adjust the flow, a choker plate *o*, with a bore of any desired size, is inserted 50 in the flanged portion *e*. As will be noted, the retarding and adjusting device may be inserted in any particular tube or tubes in the boiler. When the choker plate *o* is in position the gas impinges against 55 it and its flow is retarded thereby retaining the gas in the tube for heat producing purposes.

When it is desired to clean the tube, a wire brush or other cleaning device may be inserted through the bore of the choker plate or the choker plate may be easily removed. The beveled portion *h* reduces the interference that would otherwise occur at this point.

It is not desired to limit the invention to

the particular modifications described and illustrated herein, but the appended claims are intended to cover all variations of the invention which may be made from the principle herein disclosed.

70

I claim:

1. A device for retarding and adjusting the flow of gas in boiler tubes comprising a tubular body portion, a tubular section projecting from the body portion, and removable means carried by the device to retard and adjust the flow of gas.

75

2. A device for retarding and adjusting the flow of gas in boiler tubes comprising a tubular body portion, a flanged portion, said portions having an opening smaller in diameter than the opening in the boiler tube, and removable means carried by the flanged portion to retard and adjust the flow of gas.

80

3. A device for retarding and adjusting the flow of gas in boiler tubes comprising a tubular body portion, and a flanged portion, said portions having an opening smaller in diameter than the opening in the boiler tube, and a plate slidably mounted in the flanged portion to retard and adjust the flow of gas.

85

4. A device for retarding and adjusting the flow of gas in boiler tubes comprising a tubular body portion, a tubular flanged portion, said flanged portion having a circumferential slot, and a plate slidably mounted in said circumferential slot and having an opening smaller in diameter than the opening in the flanged portion.

90

5. A device for retarding and adjusting the flow of gas in boiler tubes comprising a tubular body portion, a flanged portion, a removable plate carried by the flanged portion, and means to permit the insertion and removal of said plate in said flanged portion without interfering with the adjacent tubular or flanged portion.

105

6. A device for retarding and adjusting the flow of gas in boiler tubes comprising a tubular body portion tapered and slit longitudinally, a flanged portion having its face beveled, said flanged portion having a circumferential slot cut at the same angle as the face of the flanged portion, and an apertured plate for insertion in said slot.

110

7. A device for retarding and adjusting the flow of gas in boiler tubes, comprising a tubular body portion tapered longitudinally, said body portion having a longitudinal slot to enable it to contract and expand, and having a beveled inner edge to facilitate longitudinal movement of a cleaning device, a flanged portion having a beveled face, said flanged portion being slotted for one half its circumference at the same angle as the beveled face, said flanged portion being grooved on its interior surface for the other half of its circumference, said slot

115

120

125

130

and groove being in alignment, said body and flanged portions having an opening smaller in diameter than the opening in the boiler tube, and a plate mounted slidably in 5 said flanged portion, said plate comprising an enlarged portion terminating in a shoulder at each side and a smaller portion, said shoulders adapted to rest on seats formed by the lower section of the flanged 10 portion, and said plate having an opening of any desired size.

8. A device for retarding and adjusting

the flow of gas in boiler tubes comprising a tubular body portion tapered and slit longitudinally, a flanged portion, said flanged 15 portion having a circumferential slot and being grooved on its interior surface, said slot and groove being in alignment, and an apertured plate for insertion in said slot and said groove.

In testimony whereof, I hereunto affix 20 my signature.

FREDERICK W. POPE.
